UNITED STATES PATENT OFFICE.

WILLIAM L. MILLER, OF PITTSBURG, PENNSYLVANIA, ASSIGNOR OF ONE-HALF TO CHARLES A. BACKSTROM, OF NEW YORK, N. Y.

ROLLER-BEARING.

SPECIFICATION forming part of Letters Patent No. 595,328, dated December 14, 1897.

Application filed March 11, 1897. Serial No. 627,046. (No model.)

To all whom it may concern:

Be it known that I, WILLIAM L. MILLER, a citizen of the United States, residing at Pittsburgh, in the county of Allegheny and State of Pennsylvania, have invented or discovered a certain new and useful Improvement in Roller-Bearings, of which improvement the following is a specification.

The object of my invention is to provide an improvement in roller-bearings; and to this end my invention consists in means for preventing objectionable movement of the rollers and diminishing friction, wear, and noise in roller-bearings.

In the accompanying drawings, which illustrate an application of my invention, Figure 1 is a perspective view of a roller provided with my improvement; Fig. 2, a central section through a bearing-box with a shaft passing therethrough and supported by a roller-bearing provided with my improvement; Fig. 3, an end view of the bearing shown in Fig. 2 with one of the end plates or bonnets removed. Fig. 4 is a sectional view of one of the rollers.

As shown in Fig. 2, the pillow-block, pedestal, or bracket 1 is provided with a cylindrical opening 2, in which is located a cage or frame comprising the longitudinal bars 3 and the annular end plates 4, which may be formed integral with the bars 3. The ends of the bearing-box are closed by the plates 9, which are bolted in place. In the spaces between the bars 3 are placed cylindrical rollers 5, with which the shaft 6 engages and by which it is supported.

The rollers 5, as shown in the drawings, are hollow and are each formed of a coiled strip of metal with any desired number of helical turns 8 in order to secure elasticity and to permit the rollers to yield laterally in case of any slight dislocation from a position of parallelism with the axis of the shaft 6. For this purpose the construction of the roller 5 is substantially that of a helical coiled spring with a comparatively narrow space 7 between the coils to permit the necessary movement of the parts of the roller relative to one another when subjected to lateral strains. A spring-roller so formed is not broadly new and is not herein broadly claimed as being of

my invention. It is found in practice that the helical coils tend to give the roller an endlong movement as the roller is turned on its axis, and the ends of the rollers are thereby forced into contact with the annular plates 4 of the frame or with the ends of the bearing-box in which they are located, and the result is a grinding action of the ends of the rollers against the part on which they bear, which results in a great deal of noise, friction, and wear, both the ends of the rollers and the plate 4 or bearing-box being rapidly worn away.

The endlong movement of the roller is due to the helical form by which when rotated it operates as a screw which is turned in a fixed nut. The object of my invention is to prevent this endlong movement, and for this purpose I provide the roller with a shallow helical groove of substantially the same pitch as the helix formed by the strip of coiled metal, the direction of which is the reverse of that of the helix formed by the coiled strip of metal—that is to say, if the strip of metal is so coiled as to operate in the manner of a right-handed screw-thread the shallow groove, which is formed in the roller for the purpose of counteracting the effect of the coiled metal, will be so formed as to operate in the opposite direction and tend to move the roller in a direction opposite to that in which it would be moved if the shallow groove were omitted.

In Figs. 1 and 2 the helical space between the coils of metal of which the roller is composed is indicated by the numeral 7 and the oppositely-curved shallow groove is indicated by the numeral 10.

I have found in practice that a helical spring-roller bearing provided with my improvement is relieved of all of the objectionable features due to the tendency of the roller to move endwise, and that the effect of the groove 10 is to keep the rollers in a central position and thereby to avoid wear of the ends of the rollers and the accompanying friction and also wear of the end plates or movement of the frame in the box.

While it is preferred in ordinary horizontal bearings that the groove 10 should have the same pitch as the helix of which the roller is composed, it may be desirable under some

circumstances to provide a groove of some-
what different pitch. For example, in case of
a vertical bearing or a bearing which is suffi-
ciently inclined to be effected by the action
5 of gravity it may be desirable to give the
groove such a pitch as to compensate for the
action of gravity on the rollers. I therefore
wish it to be understood that my improve-
ment is not limited to a construction in which
10 the pitch of the groove corresponds exactly
with that of the helix formed by the coiled
metal.

While my improvement is specially in-
tended to be employed with a coiled roller-
bearing and for the purpose of counteracting
15 the defects of such bearing, it may be em-
ployed with other forms of rollers or roller-
bearings, and in some instances its employ-
ment may be found desirable in bearings pro-
20 vided with rollers formed of solid or tubular
pieces in case a slight movement or tendency
to move in an endlong direction may be
found desirable.

My invention may be regarded as compris-
25 ing any form of helix or helical groove or pro-
jection tending to give movement in one di-
rection to a cylindrical roller forming part of
a roller-bearing, whether this tendency is or
is not opposed by some other means tending
30 to give motion in the opposite direction.

It will be understood, of course, that the
formation of a helical groove in the metal in-
volves corresponding helical projections on

each side of the groove, and any helical pro-
jection in the nature of a screw-thread simi-
larly involves the formation of a helical groove
35 or space between the projections or threads.

I claim as my invention and desire to se-
cure by Letters Patent of the United States—

1. A roller adapted to form part of a roller-
bearing, and provided with spaces and a helical
40 groove adapted to automatically resist
endwise movement and to retain the roller in
position, substantially as set forth.

2. A roller having a helically-formed space 45
on its outer surface, and an oppositely-formed
groove, tending to resist endwise movement
of the roller, substantially as set forth.

3. A roller formed of a helically-coiled strip
of metal and having a groove oppositely 50
formed to the winding of the strip, substan-
tially as set forth.

4. The combination, in a roller-bearing, of
a series of cylindrical rollers each formed of
a helically-coiled strip of metal, adapted to 55
be engaged by, and to support a rotating
shaft, and each having a helical groove
formed therein, to resist the tendency of the
roller to endwise movement, substantially as
set forth.

In testimony whereof I have hereunto set
my hand.

WILLIAM L. MILLER.
